Patent expires May 25, 1966

13 Claims. (Cl. 51—32)

1

Conventional processes and devices for producing cams on cam shafts by means of shaving tools, and in particular by grinding, are based on the so-called copying principle whereby the grinding tool is directly controlled by a master-cam machined to the utmost degree of accuracy. However, it is a well-known fact that very substantial differences are inherent to said copying process which unfavorably affect the accuracy of the cams in case of quantity production, the greatest drawback being that with increasing wear of the grinding wheel the cam profiles become more and more distorted. Hence, the grinding wheel can be worn very little and its life is very short. Theoretically the slightest wear is sufficient for causing inaccuracy.

Avoiding excessive tool costs entails defective cams which, e. g. in engines, and in particular in internal combustion engines, causes irregular cut-offs. This explains in many cases the great differences in output and performance of the motors of the same lot.

The object of the invention is the provision of a new process and a device for executing it whereby all cams of a lot are perfectly alike and the tool machining the cam operates at right angle to the curve. This applies to the grinding of the cam as well as to the turning on the lathe. A further object of the invention consists in the provision of a method and means for performing all the working operations from turning to grinding on the same machine without interrupting the continuity between turning and finishing.

In contradistinction to the true copying process the tool is controlled by a combination of control elements which are characterized substantially by two profiles of which one is used for producing the horizontal components of the tool motion and the other producing the vertical component, both however operating in a cinematically congruent manner over concentric radii of the work.

It is further of importance that with the same device geometrically similar cam profiles may be produced within certain practical limits. Since the tool carrier travels along a relative path having approximately the shape of a kidney the lengths of whose axes are at a certain proportion to each other, which may be changed for obtaining geometrically similar profiles.

The tool carrier is arranged on a rocking lever of the type of a pendulum lever the lengthening or shortening of which acts on the increase or reduction of the cam eccentricity whereby the

2

change of the cam size influences the entire shape of the cam.

Of course, this rocking lever is rotatable at one end and telescopes for assuring freedom of its movements.

Other special arrangements and details relate to the dependence and adjustment of the distances between the fulcrums of the rocking levers and their sliding guides. Furthermore, provisions are made for assuring dependence of the speeds of the motors for moving the tool support and for rotating the tool. An electric coupling has been provided, by the use of synchronous motors. In the following description all these details are minutely explained.

The drawings show embodiments of the invention by way of examples, Fig. 1 illustrating the inventive principle of the process in the basic position, Fig. 2 in a position in which the work has revolved through a certain angle, Fig. 3 representing the position for machining the vertex of the cam, and Fig. 4 the machining position of a further cam flank or face. Fig. 5 illustrates the relative path of the control and the curve along which the tool frame (or support) is displaced. Figs. 6 and 7 illustrate diagrammatically the principle according to which the control is adapted to the size of the cam to be produced. Fig. 8 is a side elevation, partly in section of the machine according to the invention, Fig. 9 a plan view of same with the gear box opened, and Fig. 10 a front view of the machine.

Referring to Fig. 1 W is the work contacted by the tool S in point 1. Since the point 1 is situated on the connecting line MO, and also on the concentrical arc 1—7, the tool S e. g. a grinding wheel occupies the zero or starting position and the centre Sm of the tool S is located on the line n, which is normal to the arc. If the work rotates with the angular velocity ω around M, the control members or the master-cams N₁ and N₂ must rotate with the angular velocity $\omega_1 = \omega$. The control members N₁ and N₂ must be designed in such a manner that the centre of the tool Sm is always located on the perpendicular to the curve.

Various preferred points of the periphery of the work are designated by the numerals 1—7, the respective perpendiculars to the curve being designated by the letters n₁—n₆ whereby the perpendicular n₁ is coordinated to point 1 as well as 7. Furthermore the angles between these perpendiculars to the curve n₂—n₆ and the zero line OM are designated by α_2 — α_6 , the corresponding

3

points of the master-cam or the control member N_1 by $1'-7'$, and the corresponding centres of the temporary eccentricities between $1-2$, and $6-7$ by M_1 and M_2 , and between $1'-2'$, and $6'-7'$ by O_1 and O_2 .

Points 3, 4 and 5 have been selected for demonstrating the operating conditions at the moments of their machining. The perpendicular n_3 to the curve at point 3 encloses angle α_3 with the axis x which is also the perpendicular to the curve n_1 in the initial position. If the work is turned through angle α_3 into the position according to the Fig. 2 the perpendicular to the curve is moved to horizontal position. The cam N_1 moves the link K_1 into the position 3' whereas the cam N_2 controls the link K_2 in such a manner that the center S_m of the tool is lifted by the distance b_3 , b_3 signifying the distance of the perpendicular to the curve n_3 from the connecting line MO (Fig. 2) which is identical with the perpendicular to the curve n_1 in the starting position. Hence the tool center is located on the perpendicular n_3' to the curve portion 3' of cam N_1 . Line n_3' is identical with the perpendicular n_3 of Fig. 1 turned into the horizontal direction.

If the work turns clockwise through angle α_4 , the link K_1 is moved by the cam N_1 to its maximum displacement to the right and the vertex of the cam at 4 is machined. By the rotation through the angle α_4 point 4 has arrived at the position according to Fig. 3. In this position the perpendicular n_4 must have reached the zero position n_4' which is identical with the line MO whilst the cam N_2 has moved the link K_2 to the vertical zero position.

Further rotation of the work from the position according to Fig. 1 through the angle α_5 to the position in which the perpendicular n_5 to curve 5 assumes position n_5' , causes the cam N_1 to move the link K_1 into the position illustrated in Fig. 4 whereas the cam N_2 lowers the link K_2 through the distance b_5 whereby the center S_m of the grinding wheel S is equally lowered. Link K_2 has now reached its lowermost position and returns therefrom to the zero position $x-x$ according to Fig. 1. While the concentric circular arc 7-1 is machined neither the link K_1 nor the link K_2 will be moved, the two cams N_1 and N_2 having a circular arc portion for this purpose. After point 1 of the work W has reached the initial position shown in Fig. 1 the movements described above are repeated.

The relative path of the tool is shown in Fig. 5, in which B designates the long axis and A the short one. The positions corresponding to the points 1-7 of the periphery of the work W are designated by $1'', 3'', 4'', 5''$ and $7''$. The horizontal components h of the movement are produced by the cam N_1 and the analogous vertical components v by the cam N_2 .

In practice, there are a great number of geometrically similar cams or profiles. Irrespective of whether these profiles are derived from so-called master-cams or are produced by a kinematic process it is sufficient to produce in the machine or device but one relative path of the tool. This is explained by the fact that for geometrically similar profiles the relations $A:B$ of the relative path according to Fig. 5 is constant. If therefore a geometrically similar profile is to be produced whereby however the lift of cams N_1 and N_2 may be more or less high than the original profile, it is possible according to a further development of the invention to adjust

4

the lift of the two cams continually whereby the relation $A:B$ is maintained.

The Figs. 6 and 7 illustrate diagrammatically an embodiment of the invention.

By means of the so-called master-cam N_1 the horizontal movement of member K_1 is controlled, its stroke being equal to $A/2$. The oscillating member T is pivoted to member K_1 and member T is rotatably supported at the point O_{s1} in the slide S_1 . On the oscillating member T a ball bearing G_2 is provided which is supported by the slide $L_{1\frac{1}{2}}$. If slide K_1 moves by the distance $A/2$ the slide L_1 moves by the distance $A_1/2$ for a specified relation of the distance $x_1:x_2$. For maintaining the geometrical relations telescopes T_1 and T_2 are inserted between points G_1 and G_2 , and G_2 and O_{s1} . If it is desired to change the stroke $A_1/2$ the slide S_1 the movement of which is indicated by the double arrow p is displaced e. g. by rotation of a self-locking threaded spindle G_{sp1} (indicated by dot dash lines in the drawing) whereby the relation $x_1:x_2$, and consequently the relation $A/2:A_1/2$ is altered.

According to the shape of the relative path in Fig. 5 member K_1 produces also the vertical movement. If the device is arranged in such a manner that the proportion $x_3:x_4$ is equal to $x_1:x_2$ (Fig. 7) the slide L_1 will move along an enlarged or a reduced relative path. For adapting the invention to a device of this kind, the oscillating member T_2 slides according to Fig. 7 in a guide of member K_1 by way of a pendulum ball bearing P_{K1} and in the slide L_1 by way of a pendulum ball bearing P_{K2} .

If the centers O_{s1} and O_{s2} according to the Figs. 6 and 7 are uniformly displaced a uniform reduction or increase of the length of the axes A and B will take place. For this purpose it is advisable to connect the threaded spindles G_{sp1} and G_{sp2} by means of toothed wheels.

There is a number of profile kinds mostly of kinematic origins in which the relative path is produced by the rotation of two different eccentricities in such a manner that from one eccentric the horizontal component is derived and from the other only the vertical component. According to whether a two-cornered, three-cornered, or n -cornered profile must be produced, the relation $A:B$ will be equal to $1:2$, $1:3$ or $1:n$.

By the present invention the relative path according to Fig. 5 may be derived from only one circular movement. It is only necessary to displace the slides S_2 and S_1 by different distances. This is accomplished by providing different toothed wheel gears between the spindles G_{sp1} and G_{sp2} . For grinding an n -cornered part the ratio of transmission $1:n$ is employed.

The Figs. 8-10 illustrate by way of example a device or machine embodying the invention.

By way of a toothed wheel gear Z_1 , Z_2 and Z_3 motor MO , drives an exchangeable cam drum N . By means of the links K_1 the cam drum N displaces the slide K in horizontal direction. To the straight-guided slide K a vertical guide F_1 is screwed, on which the link K_2 is free to glide up and down. If link K_2 is moved according to the shape of cam N_1 the pendulum ball bearing P_{K1} will participate in the movement. As the guide F_1 moves horizontally, the link K_2 glides over the ball bearing P_{K1} without any effect (Fig. 8). The vertical component of the relative path is transmitted by way of the pendulum ball bearing P_{K2} and the oscillating member T_2 rotatable about O_{s2} to the swinging body and the tool carrier S_w . The horizontal movement of the body K is trans-

mitted by way of the oscillating member T rotatable about OS₁ and by way of the ball bearing G₂ to the straight-guided slide L₁ and the guide F₂. Consequently the swinging body S_w will travel along the reduced or increased resulting relative path.

For altering the relative path the threaded spindles G_{SP1} and G_{SP2} are revolved. This is done by hand by a hand wheel (Fig. 10) fitted with a scale disc SK by way of exchangeable spur gear wheels R₁ and R₂ acting on the threaded spindles G_{SP1} and G_{SP2}. Thereby the slides S₁ and S₂ are displaced. This continuous adjustment of the strokes provides for utmost precision. Swing body S_w glides between two lateral walls W₁ and W₂, and rests on ball-bearings K_g, which are guided by coupling rods St. The pressure on the guides is obtained by a spring Z_f and the reaction of the tool pressure.

In the embodiment of the invention in a universal cam turning and grinding machine the entire swinging body S_w may be rotated about a pin A_s whereby either the grinding wheel S or the tool holder D_{st} may be applied. The swinging body may be clamped in any position within its range of movement.

The grinding wheel S is driven through the belt R_t by a motor M₀₂ located on the swinging body S_w. As the swinging body S_w must be moved at a certain ratio to the speed of the work the two motors M₀₁ and M₀₂ (Fig. 10) must be coupled mechanically or electrically. In the present case two synchronous motors have been provided.

In other respects the design of the machine is the same as that of a conventional grinding machine having a head stock 11, a bed 12, and puppet 13.

I claim:

1. A machine for machining cams including a work holder, a movable tool holder, two rotating master cams, means interconnecting said cams and said tool holder for moving it horizontally under the influence of one cam and vertically under the influence of the other cam, and means connected with said first means for varying the magnitude of the horizontal and vertical movements of the tool holder.

2. A machine for machining cams including a work holder, a movable tool holder, two rotating master cams, means interconnecting said cams and said tool holder for moving its horizontally under the influence of one cam and vertically under the influence of the other cam, and means connected with said first means for varying individually the magnitude of the horizontal and vertical movements of the tool holder.

3. A machine for machining cams including a work holder, a movable tool holder, two rotating master cams, means interconnecting said cams and said tool holder for moving it horizontally under the influence of one cam and vertically under the influence of the other cam, and means connected with said first means for varying simultaneously the magnitude of the horizontal and vertical movements of the tool holder.

4. A machine for machining cams including a work holder, a movable tool holder, two rotating master cams, means interconnecting said cams and said tool holder for moving it horizontally under the influence of one cam and vertically under the influence of the other cam, and means connected with said first means for varying simultaneously the magnitude of the horizontal and vertical movements of the tool holder, the

variation of the horizontal movement being different in magnitude from that of the vertical movement.

5. A machine for machining cams comprising a rotatable work holder, stationary bearing means for said holder, a tool holder, a movable support rotatably supporting said tool holder, a stationary base member vertically slidably connected with said support, a horizontally swingable lever member, a vertically swingable lever member, pivot means connected with said base member and individually swingably supporting said lever members, connecting means movably connected with said lever members and with said support for transferring the motions of said lever members to said support, a cam shaft rotatably supported by said base member, two master cams fixed on said shaft, a slide member horizontally slidably connected with said base member and movably connected with said first lever member and having a cam follower portion engaging one of said master cams, a second slide member vertically slidably connected with said first slide member and movably connected with said second lever member and having a cam follower portion engaged by the other master cam, and drive means connected with said work holder, with said tool holder, and with said cam shaft for driving these parts in synchronism.

6. A machine as defined in claim 5, having individual electric synchronous motors for rotating said work holder, said tool holder, and said cam shaft.

7. A machine as defined in claim 5, comprising individual support means for said pivot means movably connected with said base member and being individually displaceable in the direction of the longitudinal axes of said lever members for adjusting the leverage thereof.

8. A machine as defined in claim 5, comprising individual support means for said pivot means movably connected with said base member and being individually displaceable in the direction of the longitudinal axes of said lever members for adjusting the leverage thereof, and a common drive means for said support means for moving same simultaneously.

9. A machine as defined in claim 5, said lever members comprising telescoping portions for affording free movement of the connections of said lever members with said support and with said slide members.

10. A machine for machining cams comprising a rotatable work holder, stationary bearing means for said holder, a tool holder, a movable support rotatably supporting said tool holder, a stationary base member vertically slidably connected with said support, a horizontally swingable lever member, a vertically swingable lever member, connecting means movably connected with said lever members and with said support for transferring the motions of said lever members to said support, a cam shaft rotatably supported by said base member, two master cams fixed on said shaft, a slide member horizontally slidably connected with said base member and movably connected with said first lever member and having a cam follower portion engaging one of said master cams, a second slide member vertically slidably connected with said first slide member and movably connected with said second lever member and having a cam follower portion engaged by the other master cam, drive means connected with said work holder, with said tool holder, and with said cam shaft for driving these

parts in synchronism, individual pivot means individually swingably supporting said lever members, guide means connected with said base member and horizontally, individually slidably supporting said pivot means for displacement thereof in the direction of the longitudinal axes of said lever members, and self-locking displacing means connected with said pivot means for displacing said pivot means for changing the leverage of said levers.

11. A machine for machining cams comprising a rotatable work holder, stationary bearing means for said holder, a tool holder, a movable support rotatably supporting said tool holder, a stationary base member vertically slidably connected with said support, a horizontally swingable lever member, a vertically swingable lever member, connecting means movably connected with said lever members and with said support for transferring the motions of said lever members to said support, a cam shaft rotatably supported by said base member, two master cams fixed on said shaft, a slide member horizontally slidably connected with said base member and movably connected with said first lever member and having a cam follower portion engaging one of said master cams, a second slide member vertically slidably connected with said first slide member and movably connected with said second lever member and having a cam follower portion engaged by the other master cam, drive means connected with said work holder, with said tool holder, and with said cam shaft for driving these parts in synchronism, individual pivot means individually swingably supporting said lever members, bearing means for said pivot means, stationary guide means horizontally, individually slidably supporting said bearing means for displacement thereof in the direction of the longitudinal axes of said lever members, and individually threaded spindles screwed individually into said bearing means for displacing same upon rotation of the spindles.

12. A machine for machining cams comprising a rotatable work holder, stationary bearing means for said holder, a tool holder, a movable support rotatably supporting said tool holder, a stationary base member vertically slidably connected with said support, a horizontally swingable lever member, a vertically swingable lever

member, connecting means movably connected with said lever members and with said support for transferring the motions of said lever members to said support, a cam shaft rotatably supported by said base member, two master cams fixed on said shaft, a slide member horizontally slidably connected with said base member and movably connected with said first lever member and having a cam follower portion engaging one of said master cams, a second slide member vertically slidably connected with said first slide member and movably connected with said second lever member and having a cam follower portion engaged by the other master cam, drive means connected with said work holder, with said tool holder, and with said cam shaft for driving these parts in synchronism, individual pivot means individually swingably supporting said lever members, bearing means for said pivot means, stationary guide means horizontally, individually slidably supporting said bearing means for displacement thereof in the direction of the longitudinal axes of said lever members, individually threaded spindles screwed individually into said bearing means for displacing same upon rotation of the spindles, a spur gear wheel connected with each spindle, the teeth of one wheel registering with the teeth of the other wheel, and a common drive for said wheels.

13. A machine as set forth in claim 12, said gear wheels having different diameters and tooth numbers for changing the leverage of said lever members in a different degree.

ROBERT MUSYL.
